UNITED STATES PATENT OFFICE

2,101,637

MULTIPLE ACTION THERMOSTAT

George Howlett Davis, Washington, D. C.

Application August 23, 1935, Serial No. 37,421

16 Claims. (Cl. 200—138)

This invention relates to multiple action thermostats and in its application to automatic thermoelectric fire alarms the principle herein involved is illustrated and described in the modified structures of my applications for United States patents given Serial Number 732,172, filed June 23, 1934, and Serial Number 8,776, filed February 28, 1935. This application is a continuation in part of my two said co-pending applications.

The present invention has numerous applications or uses and is susceptible of many modifications other than those just mentioned and those shown and described herein without avoiding the spirit of the discovery.

When used as a local detector of accidental fires in conjunction with distant signals or annunciators in circuit therewith the fixed thermostat would be adjusted with micromatic accuracy to function in its expansible movement at any predetermined temperature ranging from say 60° F. to 160° F., but preferably is factory set at 110° F. for household, hotel and other like usages where the device is designed to give timely warning of the impending danger. In the usages just named the rate-of-rise or quick-acting thermostat, in event of a fast fire, would function in advance and independently of the fixed thermostat and generally within from one to five seconds from the time of the starting of this most dangerous form of accidental fire. The lowering temperature thermostat acts independently of both the fixed and the rate-of-rise thermostats, all as will now be more particularly described.

In the accompanying drawing like numerals of reference thereon indicate corresponding parts which appear in two or more of the views, wherein—

40 Fig. 1 is a perspective view of my round form of multiple action thermostat with the casing or cover in operative position.

Fig. 2 is a plan view of the interior of the structure below lines 2—2 of Fig. 3.

45 Fig. 3 is a transverse vertical section of Fig. 1.

Fig. 4 is a perspective view of my multiple action thermostat arranged in a casing of rectangular shape with several of the parts shown in Figs. 1, 2, and 3 omitted.

50 Fig. 5 is a plan view of the structure of Fig. 4 with the cover removed in order to show clearly the interior parts.

Fig. 6 is a bottom view of the structure of Figs. 4 and 5.

Referring specifically to the round form of

my device as by Figs. 1, 2, 3, I provide a cup-shaped casing 10, which is preferably made of insulating material, such as molded Bakelite, provided with a cover 11, preferably of stamped out sheet Bakelite, and secured by the screws 11a to the casing 10. The widely spaced holes 11b and the closely arranged series of holes 11c are stamped thru the cover 11 in the same operation which punches the holes therein for screws 11a, and blanks out the cover. In the bottom of the 10 casing 10 (see Fig. 3) is molded the closely arranged series of holes 10b which are in vertical registry with the holes 11c of the cover 11.

What I term the rate-of-rise or the quick-acting thermostat comprises mainly the arch shaped 15 and relatively thin bimetal blade 12 and its co-acting parts, as will now be more particularly described. The said bimetal blade 12 is secured at one end to the binding post 13 supported by the panel disc 19 of sheet Bakelite and having a 20 series of holes therein, 19a as shown, in vertical alignment with and similar to the series of holes 11c or 10b. The said blade 12 is aligned as shown between the three series of inlet holes last described and has at its free end the contact point 25 12a.

What I term the fixed thermostat, in its application to the round form of my device, comprises the bimetal blade 14 secured and supported at one end by the swivel binding post 15 and having at its longer free end 14a the two contact points 14b and 14c, its short free end 14d, being bent outwardly, all as more clearly shown in Fig. 2. The longer free end 14a bends expansibly or outwardly under a rising temperature until its 35 contact point 14b impinges the contact point 16a upon the end of the adjustment screw 16b supported in the binding post 16 set in the insulated panel disc 19. The coil spring 17 serves to normally hold the short end 14d of the blade 14 40 against the stop post 20 and this spring also serves as a metallic connection between the post 20 and the swivel binding post 15. Under a lowering temperature the blade 14 bends contractively or inwardly and when the ambient atmosphere reaches a predetermined temperature of say 68° F. the contact point 14b completes circuit thru the contact point 18a in adjustment screw 18b in binding post 18 which latter is anchored in the panel disc 19. In the stop post 20 50 is an adjustment screw 20a by means of which the contact points 14b and 14c are adjusted in any desired spaced relation to all other contact points, viz 12a, 16a, 18a. All supporting binding posts are preferably riveted in position on the 55

panel disc 19 as otherwise the great vibration set up in the device when actuating would loosen securing nuts.

In the round form of my device I may secure 5 to the upper side of the panel disc 19 the two blade contacts 21a, 21b, for the reception of the plugs 22a, 22b of the plug 22, which may be of any standard or special design and the connecting wires 22c, 22d of which are preferably connected in multiple with a distant alarm, signal, annunciator box, or other controlled mechanism 10 designed to perform any usual or special function. The connection to the latter mechanisms may be made thru a relay or transformer thus 15 permitting of employing thru the extension plug currents of different voltage from that which actuates the multiple action thermostat.

In the round form of my thermostat I also may 20 employ a metal push button 23 supported by the casing 10, the stem 23a being encased in a delicate expansion coil spring 23b which keeps the ferrule 23c normally pressed against the inside of the casing 10 and in juxtaposition with the short free end 14d of the bimetal blade 14, as 25 clearly shown in Fig. 2, so that when the button 23 is manually pressed inward the longer free end 14a of the blade 14 is moved with its contact point 14b against the contact point 16a, thus completing the circuit thru the device and all 30 the mechanisms in the circuit and causing the latter to actuate. This provides a simple and effective method of testing both the operativeness of the devices in circuit and ascertaining whether the source of supply is alive.

35 The rectangular form of my device, as shown in Figs. 4, 5, and 6, is simpler than the round form just described in that it does not embody the extension plug 22, or the testing button 23, but it is obvious that these elements may readily 40 be added to the rectangular form. In its rectangular form a thin partition wall 24 is provided which acts as a division wall or baffle plate in the dissemination of inflowing heated air when moving at a relatively rapid speed, such as occurs 45 during a fast fire and serves to cause such currents of air assisted by the specially arranged inlet openings 25a, 26a, to first heat the bimetal blade 12 sufficiently to cause it to move towards and contact with the blade 14 before the latter 50 is heated sufficiently to cause it to move out of the way, while in the case of a slow accidental fire accompanied by a relatively slow movement of the heated air without and within the casing such air is disseminated almost uniformly 55 throughout the casing thus causing the blade 14 to move towards the contact 16a and complete circuit therewith before the uniformly moving blade 12 can catch up with and form contact with the blade 14, all as more clearly shown in 60 Fig. 5.

65 The peculiar continual pursuing, in both forms of my device, of the free contacting ends of the two bimetal blades 12 and 14 as hereinbefore described is mostly due to the special arrangement and number of the inlet openings of the casing which differentially affect different areas within the casing according to the different speeds of movement of the heated air within the casing, all as substantially shown and described. The 70 round form of casing needs no partition wall 24 because its blades are oppositely disposed within the casing, while in the rectangular casing the two blades 12, 14 are arranged in close parallelism, and without the thin partition 24 both

would be similarly affected by the varying speeds of movement within the casing. The two bimetal blades 12, 14, of the rate-of-rise and fixed thermostats are shown in Figs. 5 and 2, respectively, in the positions they assume when factory adjusted at a temperature of 70° F. The casing 26, or rather its body portion, is preferably formed of an integral Bakelite molding and embodies holes for the various binding posts, and screws as well as the series of holes 25a. 10

When designed for closing low voltage currents either my round or rectangular shaped casing may be employed as shown, but when used for closing currents of over 90 volts then the thermostats would be encased in a terminal box of 15 any standard approved form.

In instances where it is desired to employ my improved device as an automatic thermoelectric detector sounding a separate alarm or signal for 20 also operating home or other heating units then the contact 14b of the round form casing would be spaced so that when the temperature drops to say 68° F. a separate circuit would be completed between contacts 14b and 16a thereby actuating a draft opener or performing more complicated functions. By the use of a step-down transformer householders could run bell wiring to open the draft door of their small furnaces, but preferably electricians would make such connections even for small homes. All this could 25 be done without in the least interfering with the operation of the device as a fire detector and alarm actuator of the multiple action thermostat type which requires no servicing, which latter objection becomes serious in installations for 30 small homes where the cost of periodical servicing would become a serious objection.

In all instances the casing for the thermostatic blades should be air tight except for the several 40 series of inlet holes, 10b, 11a, 19a, 25a, 26a, and those thru the panel disc 19, and the most efficient arrangement of such inlet holes can only be obtained thru experimenting upon every change in the shape of the casing and the location of the two thermostatic blades. 45

Having described two forms of my multiple action thermostat with particular reference to their structural features I will now endeavor to elucidate their modus operandi with special reference to the essential principles involved, including the air directional means employed. First, suppose that one of my thermostats is located at or near the ceiling of a bed room in a residence or hotel where the door and windows are closed, and that an accidental fire starts 50 therein. Then such fire will gain force but slowly because of the lack of an air draft and the heated air will rise and move about the room, principally at the ceiling, slowly, as likewise within the casings 10, 25 of my devices and resulting in a nearly uniform distribution of the air therein. This causes both the fixed and rate-of-rise bimetal blades 14, 12, to bend outwardly or towards the fixed contact point 16a at a nearly uniform rate until the blade 14 impinges said contact point and completes circuit therewith. Next suppose that a fire starts in the same room under like conditions except that the door and windows are open, then the initial flame will be 55 "fanned" with gathering force into a disastrous conflagration, all as is generally well known. Under the last named conditions the now rapidly moving heated air would enter the casing of my device thru some of its inlet openings and 60

pass out through others thus setting up a draft of heated air within the casing with the major volume of the heated air passing in a nearly straight line between the points of the casing 5 having the larger or more numerous air inlets and causing the bimetal blade 12 of such draft to first become heated and cause it to overtake and make contact with the scarcely moving blade 14. The surplusage of heated air would pass 10 around my device. The wells of open stairways are veritable draft creators and these vulnerable points should be protected by locating one of my thermostats upon the ceiling directly at the top of the stairway where a maximum movement of 15 heated air would pass from rooms and other places below and in which instance my rate-of-rise thermostat would generally operate ahead of the fixed thermostat for the reasons given.

A "slow" or "ordinary" fire as I have employed 20 the terms herein may be defined as one in which the temperature rises at the rate of from 1° F. to 4° F. in one minute at the ceiling and where the heated air moves from one point to another at the speed of from four to twenty yards per minute. 25 At this slow movement a relatively small volume of the heated air would, in the case of my round form of device, enter the small and widely spaced inlets 11b, while a considerably larger volume would enter slowly the larger and 30 more numerous inlets 10b and pass upwardly thru the inlets 19a and out at the inlets 11c, or the direction of the slowly flowing heated air may be reversed. In any event the slow passage 35 of heated air thru the casing 10 would cause it to distribute itself almost uniformly within the casing much as it would be doing in the room where the "slow" fire had started. Under these conditions the bimetal blades 12, 14 would bend in the same direction at a nearly uniform rate 40 and thus preserve their original spaced relation until the blade 14 was stopped in its movement by contact with the point 16a when the blade 12 would catch up with it and help hold it in a circuit closing position.

45 Now a "fast" "rapid" or "hot" accidental fire is one during which the temperature rises from 6° F. to 20° F. per minute accompanied by a heated air movement of from 25 to 125 yards per minute. Only a small volume of this rapidly moving heated 50 air can enter the casing 10 and naturally the greater part of this volume passes thru the inlets 10b, 19a, and 11a in a nearly straight line and it is within this line or "draft" of heated air that the rate-of-rise bimetal blade 12 is located and 55 under which conditions it completes circuit in from one to five seconds after the starting of a "fast" fire.

The first act of expert firemen upon reaching 60 a "fast" fire is to stop all drafts possible while my device induces air drafts within its casing at all times but controls the direction of such drafts in the manner, by the means and for the life and property saving purposes herein described.

65 I claim;

1. A multiple action thermostat for actuating 70 electrically operated mechanisms in circuit therewith said thermostat comprising a bimetal blade which acts as a fixed thermostat and operates under slow or ordinary accidental fire conditions at a predetermined temperature for which it has been adjusted, a secondary quick-acting bimetal blade acting as a rate-of-rise thermostat and which operates independently under any sudden 75 increase in the speed of movement of the heated

air, and means for directing said rapidly moving heated air first and mostly against the said secondary bimetal blade.

2. A multiple action thermostat comprising two bimetal blades operatively associated within a casing provided with two sections with a thermostatic blade in each of the casing sections and with air passages located in the wall of only one of the sections in a manner to differentially affect the two blades by varying the direction of movement of the superheated air arising from a conflagration from the outside of the cover to the inside thereof under varying accidental fire conditions and whereby one blade closes the operating circuit at a predetermined temperature under 10 conditions produced by a slow or ordinary fire, said means also causing the other bimetal blade to act more quickly than the first whenever a relatively fast accidental fire occurs and sets a relatively fast movement of the heated air from 20 without to within the casing.

3. A multiple action thermostat comprising two bimetal blades supported within a casing provided with two sections with a thermostatic blade in each of the casing sections and with air passages 25 located in the wall of only one of the sections in a manner to differentially affect the two blades, one of which blades acts independently of the other as a thermally operated switch responsive to a relatively slow rate-of-rise and movement 30 of the ambient air caused by a slow or ordinary fire when the slow movement of the air within the casing allows the air to be uniformly distributed within the casing, and means causing the air arising from a relatively fast fire to be first and mainly directed against or around the second blade and cause it to make a circuit completing contact with its companion blade before the latter can move out of contacting relation 35 with said first blade.

4. A directional air-drafted thermostat comprising a casing provided with two sections, air vents in the wall of one of said sections, a primary blade in one of the sections and a secondary blade in the other of the sections, said blades being 45 bendable in the same direction and plane at their adjacent free ends under the influence of heated air entering said casing, the said air vents serving to cause a relatively uniform distribution of the air entering the casing under conditions attendant 50 upon a slow accidental fire when the said adjacent free ends will preserve substantially the same spaced relation to each other, while the said air vents under the conditions of a relatively fast fire cause the secondary blade to overtake and 55 form contact with the primary blade before the latter can move out of the path of movement of the secondary blade.

5. In a device of the class described, the combination of a closed casing and a bimetal thermostat for controlling electric circuits within the same, of means for testing the operativeness of the electric circuits within, consisting in a push button carried in the wall of the casing having a spring provided stem engaging the bimetal blade, 60 a revolvable support upon which said blade is mounted whereby said blade is allowed to be pivotally revolved and cause the free end thereof to complete a circuit through the device and thus indicate its operativeness.

6. In a device of the character described, the combination with a closed casing, and a bimetal blade for controlling electric circuits together with a movable post on which it is carried, and means for testing the operativeness of the circuits 75

- consisting of a manual device in the wall of the casing having a resilient stem adapted to engage the blade and move it, a pivot revolvably supporting said blade so that the contact points will 5 operate to complete the circuit and thus indicate the operativeness of the device whenever the resilient stem is pressed inward.
7. In a device of the class described, the combination of a closed casing and bimetal blades 10 mounted therein operatively arranged in association with each other, and a movable pivot on which one of the blades is mounted so as to have a long arm and a short arm, means for carrying the other blade at the end thereof, and a push 15 button supported in the wall of the casing and having a yielding stem which engages the short arm of the blade so as to move the same on its pivot and cause the long arm to complete the circuit and thereby indicate the operativeness of 20 the devices.
8. A multiple action thermostat, comprising essentially the combination with a casing having two differently ventilated interior sections of bimetal blades separately arranged in each section 25 and opposite to each other, means for supporting each of said blades at contiguous ends so that the other ends carrying contacts may have free co-active movement in the same plane.
9. A multiple action thermostat comprising a 30 closed casing having one interior section freely ventilated by numerous apertures in the casing thereabouts and a restrictively ventilated interior section contiguous with the other section; a thermo-active bi-metal blade switch located in said 35 freely ventilated section proximate to or between said apertures in the casing said blade switch serving as a quick acting thermostat when cooperatively associated with a secondary thermo-active blade-switch located within the said 40 restrictively ventilated section of the casing.
10. A multiple action thermostat comprising a closed casing having one interior section thereof 45 freely ventilated by numerous apertures thereabouts in the wall of the casing, and a restrictively ventilated interior section contiguous with the other section; a primary thermo-active bi-metal blade-switch located in said freely ventilated section proximate to and between oppositely disposed apertures in the casing; a secondary 50 thermo-active bi-metal blade switch located in the restrictively ventilated section; said blade-switches moving in the same plane and preserving substantially the same spaced relation at their free adjacent contacting ends under normal or 55 relatively slow movements of heated air thru or within the casing but making circuit-completing contact with each other at their free ends whenever a fast movement of heated ambient air or relatively rapid rising temperature occurs, in 60 which event a proportionately great amount of the fast moving heated air first impinges said primary blade-switch and causes it to flex or bend towards and against the said secondary blade and complete contact therewith before the latter is caused to move out of the way.
11. A rate-of-rise thermostat, comprising essentially the combination with a casing having 5 two differentially ventilated interior sections of bi-metal blades separately arranged in each section and opposite to each other, means for supporting each of said blades at contiguous ends so that the other ends carrying contacts have 10 free co-active movement in the same plane.
12. The combination with a fixed thermostat having a casing with air passages therein, a thermosensitive blade-switch which is freely ventilated by said air passages, of a secondary thermosensitive blade-switch located in a restrictively ventilated section or compartment of said casing and having its free contacting end cooperatively associated with the free contacting end 15 of the said primary blade-switch. 20
13. A multiple action thermostat comprising a closed casing having interior sections one of said sections being freely ventilated by apertures in the casing thereabouts and a restrictively ventilated interior section contiguous with the other section, a thermo-active bi-metal blade-switch located in said freely ventilated section proximate to or between said apertures in the casing; a secondary thermo-switch blade mounted in the casing; said blade switches serving as a quick-acting thermostat when cooperatively associated 25 with each other. 30
14. A rate-of-rise thermostat comprising a casing said casing having two sections, air ventilating openings in one of the sections forming 35 two differentially ventilated sections, bi-metal blades located in each of said sections, means for mounting each of the blades at one of their ends and the other ends being free, and contacts on the free ends of the blades cooperatively associ- 40 ated with each other.
15. A rate-of-rise thermostat comprising a casing, said casing having a partition extending substantially the length of the casing forming two sections, air ventilating openings in one of the sections forming two differentially ventilated sections, thermosensitive blades arranged in each of said sections, means for mounting each of the blades at one of their ends, and the other ends being free, and contacts on the free ends of the 50 blades cooperatively associated with each other.
16. A rate-of-rise thermostat comprising a closure having two sections, air ventilating openings in one of the sections thus forming two differentially ventilated sections, thermosensitive 55 switches located in each of said sections, means for mounting each of the said thermosensitive switches at one of their ends and the other ends being free and arranged in contacting relation with each other. 60

GEORGE HOWLETT DAVIS.
